[57] CLAIM

The ornamental design for a cage, as shown and described.

DESCRIPTION

FIG. 1 is a perspective view taken from the top, front and left side of a cage showing my new design with the lid shown in a raised position;

FIG. 2 is front elevational view thereof showing the lid in its closed position;

FIG. 3 is a left side elevational view of FIG. 2, the right side being a mirror image of the left side shown;

FIG. 4 is a top plan view of FIG. 2;

FIG. 5 is a rear elevational view of FIG. 2; and

FIG. 6 is a bottom plan view of FIG. 2.

FIG 1

FIG 4**FIG 2**
